AUTOMOBILE HEATER

Walter G. Mitchell, Oak Park, and Arnold P. Hultgren, Chicago, Ill., assignors to Sears, Roebuck and Co., Chicago, Ill., a corporation of New York

Application March 10, 1939, Serial No. 260,900

13 Claims. (Cl. 93—2)

Our invention relates to automobile heaters, and has to do more particularly with an improved heater which is designed for other optional uses, including the defrosting of a windshield.

A particular object of our invention is to provide a device which is capable either of simultaneously or alternatively heating and/or defrosting at the will of an operator.

Another object is to provide a device of the type referred to which will have improved heating efficiency.

Still another object is to provide such a device wherein a portion of the heat transmitted through the heat exchange elements will be recirculated therethrough before it is discharged from the heater.

Another object is to provide a device of the type referred to wherein the shape of the air channel is so designed that the air discharged from the heater is concentrated rather than diffused, thus providing a higher temperature of air where it is especially desired.

Still another object is to provide means for controlling the temperature of defroster air.

Still another object is to provide a device of the type referred to which will be simple and inexpensive to construct, easy to adjust, efficient in operation, and generally satisfactory for the purposes desired.

Various other objects and advantages will suggest themselves to those skilled in the art, as the description proceeds.

Referring now to the drawings forming a part of this specification and illustrating a preferred embodiment of our invention:

Fig. 1 is a front perspective view of a heater embodying our invention;

Fig. 2 is a vertical axial sectional view of the same;

Figs. 3 and 4 are sectional views taken substantially along the lines 3—3 and 4—4, respectively, of Fig. 2;

Fig. 5 is a front elevational view of the same;

Fig. 6 is a perspective view of an air control plate forming a part of the front of the heater casing;

Fig. 7 is a perspective view of an air control door forming another element of the front of the heater casing;

Fig. 8 is a fragmentary sectional view taken substantially along the line 8—8 of Fig. 2; and

Figs. 9 and 10 are vertical axial sectional views of the front of the heater casing illustrating diagrammatically the air paths under different conditions of control.

In the preferred embodiment illustrated, the heater comprises a casing indicated generally by the numeral 10, in which is mounted a heat exchange unit indicated generally by the numeral 12. Mounted rearwardly of the heat exchange element is an air propelling unit indicated generally by the numeral 15.

The air propelling unit comprises a U-shaped bracket 16, from the legs of which are vertically extending ears 17, 17, to which is secured, as by screws or the like, a spider bracket 18 carrying a motor 20 and a fan unit, indicated generally by the numeral 22, keyed to the shaft 23 of the motor. The fan unit comprises a "squirrel cage" type of centrifugal blower 25, the perforated rear wall 26 of which is secured to the motor shaft 23. The front edge of the squirrel cage has outwardly extending ears 27 to which are secured as by rivets a plurality of blades 30 which are preferably integral with an annular ring 31 which seats against the front edge of the squirrel cage. The blades 30 are so arranged as to propel a current of air forwardly through the heating unit.

A circular blower housing 33 is disposed around the squirrel cage, said housing being secured as by screws or the like to the bracket 18. An outlet tube 35 communicates with the housing 33, this tube being connected to a suitable conduit 36 preferably leading to a windshield defroster, although said conduit may, of course, be directed wherever desired. A manually controlled damper 37 may be provided.

Secured to the U-shaped bracket 16, as by welding or the like, is a plate 38, which seats snugly against the rear edge of the casing 10. The plate may be secured to the casing 10 as by means of screws 41 or other suitable means and is provided with an annular flange 43 defining a circular opening which substantially conforms to the path of fan blades 30.

The heating unit 12 may be of any standard or other suitable type and, in the embodiment shown, comprises headers 45, 45, said headers being connected by tubular elements 46, heat exchange fins being carried by said tubes. A sheet of foraminous material 48 may be secured to the front of the heating unit for filtering out any trash or the like which may be drawn into the current of air.

The casing 10 comprises a shell having a substantially circular wall 50, except for the lower portion where the walls extend downwardly to form a substantially rectangular portion with a bottom wall 40, side walls 52, and a front wall 53. A front flange 54 is formed integrally with the

approximately circular portion 50. Louvers or vents 55 may be formed in the walls 52—53, said vents extending around the corners so as to permit air to be directed forwardly and laterally. Reference to Figs. 9 and 10 will show that the wall of the casing is deformed adjacent the vents 55, as indicated at 55', in order to provide outwardly and downwardly extending passages whereby warm air may be permanently directed toward a person's feet.

Studs S projecting inwardly from the front wall of the casing, and preferably having resilient jackets S' thereon, serve as bumpers or stops for the heating unit.

A plurality of bosses 57 are formed on the inside of the front wall 53 and flange 54, to which are secured as by screws or the like, spring clips 58, which serve to retain a ring 59. Preferably one clip 58 is attached to the wall 53 while two of said clips are connected to the circular flange 54, these clips being preferably equally spaced. Helical springs 56 may be seated against the clips 58 and coiled around the retaining screws, as seen best in Fig. 8, in connection with some or all of the clips. The ring 59 is provided with an annular shoulder 60, as seen best in Fig. 2, whereby it seats snugly and rotatably against an inwardly extending annular flange 61 formed on the front flange 54, said annular flange 61 continuing along the entire circumference to serve as a bearing against ring 59.

Preferably integral with the ring 59 is a radially slotted front segment 63 which, when viewed from the front, as in Figs. 1, 3, and 5, occupies substantially a semi-circle. When viewed in radial section, as in Fig. 2, the segment 63 is arcuate in form, and it will be seen that its curvature approximates that of a quadrant of an ellipse viewed along its major axis.

The radial elements of the segmental member 63 radiate from an annular member 64 from which extends inwardly a hollow substantially conical element 65, said conical element being slotted in its upper portion for about half of its periphery, as at 66.

A valve plate 68 of a contour conforming with that of the segmental element 63 is rotatably mounted on the inside thereof, being retained by a shoulder formed in a ring 69, which ring may be riveted or otherwise secured to the shoulder 60 of the segmental element. The plate 68 (Fig. 6) is provided with radial slots 70 conforming substantially with the slots of the segmental element 63, and a manipulating member 71 is secured to the upper portion of said plate, this manipulating member having a neck 72 extending through a slot 73 in the segmental member 63, whereby the plate 68 may be rotated the space of one slot so as to open or close the segmental member to the passage of air.

A pair of quadrant shaped doors 75, 75, is rotatably mounted opposite the segmental member 63, being retained by means of a groove 74 in the ring 69. These doors 75 (Fig. 7), each of which has a manipulating member 76 hereon, are substantially similar in radial section to the curvature of the segmental member 63 and the apertured plate 68 mounted therebehind. The doors 75 are mounted to be slideable behind the apertured plate 68 and may be rotated individually so as to open either one quadrant or both quadrants in the front of the casing 10. The apertured plate 68, of course, may be moved to open or close the slots in the segmental member 63 independently of the doors 75. It should also

be noted that the segmental member 63 along with the plate 68 and doors 75 may be rotated as a unit, these parts providing a substantially spheroidal surface.

Attached to the inside of the conical member 65, and substantially conforming to the contour thereof, is a hollow conical valve member 78, the latter being retained as by means of a bolt 79 or the like passing through the bases of both cones. The peripheral portion 80 of the conical element 78 is curved outwardly bell like to form a circular lip which seats against an annular shoulder 80 formed on the inside of the annular member 64. The conical valve 78 is slotted to conform to the slots 66 of the conical portion 65 and is provided with an outwardly extending cup-shaped portion 81 which serves as a handle, whereby the valve 78 may be rotated with reference to the conical portion 65 so as to open or close the slots 66. The annular member 64 is also provided with a shoulder 84 on the outer periphery thereof for seating the valve plate 68. A ring 86 is secured as by riveting or the like to the conical portion 65 and has a peripheral groove 87 formed therein for slidably seating the quadrant shaped doors 75.

In operation, the performance of the device will vary according to the positioning of the various valves and doors. Considering first a situation as illustrated in Fig. 9, wherein the valve plate 68 is positioned to close the radial apertures of the segmental member 63, the quadrant shaped doors 75 are closed, and the conical valve member 78 is positioned to close the vents 66, it will be seen that all the air projected forwardly by the fan 30 will pass through the heating unit and, except for a small portion of heated air which will escape at the bottom of the casing through the louvers 55, substantially all of the air, upon coming in contact with the closed front of the casing, will be drawn back by the centrifugal blower 25 and caused to retrace its passage through the heating unit and then blown out through the conduit 35 to a defroster or wherever else it may be directed.

Considering next a condition as illustrated in Fig. 2, wherein one or both of the quadrant shaped doors 75 is or are closed while the vents in the segmental member 63 are closed and the valve 78 is positioned to wholly or partially open the vents 66 in the conical element 65, it will be seen that a substantial portion of the air which is projected forwardly through the heat exchange unit is drawn back by the centrifugal blower, thus being reheated before it is blown out by the blower through the conduit 35. However, in this case this air which is drawn back by the centrifugal blower is diluted by cooler air drawn in through the vents 66 and which is heated by only a single passage through the heat exchange unit. Thus it will be seen that the valve 78 may be adjusted to this position when a lower temperature of air for defrosting or other purposes is desired than in the case of Fig. 9.

In the adjustment illustrated in Figs. 1 and 10, the segmental element 63 is still closed but the doors 75 are open. In this case a substantial portion of air which is directed forwardly by the fan 30 is blown out through the substantially semi-circular opening in the lower portion of the front of the casing as shown by the arrows. This illustrates the advantages as to efficiency obtained by the curved front of the casing. Instead of the air being directed straight forwardly through the heating unit and thence directly and

diffusedly out into the space to be heated, as in the ordinary heater of this type, there is projected a large proportion of heated air around opposite sides of central cone and thence downwardly against the curved surface defined by the segmental member 63. A greater concentration of warm air is thus provided at points adjacent the heater, so that the air is less diffused, and especially at points adjacent the floorboard, than in devices where it is projected directly forwardly of the heater. Thus, the more or less elliptical surface of the segmental element serves to direct downwardly or in any other direction in which the segmental member may be turned, a concentrated envelope of warm air rather than a diffused stream. It will be understood that either one of the doors 75 may be partially or wholly closed, thus further concentrating the ejected air stream.

Of course, in the arrangement of Figs. 1 and 10, the vents 66 in the conical valve may or may not be opened as desired, depending upon whether or not one wishes to dilute the air which is being drawn back by the centrifugal blower. In either event, of course, a substantial portion of air will be so drawn back for ejection through the outlet 35.

Numerous other combinations of adjustments may be made.

It will be understood that, under all circumstances, at least part of the air which is ejected by the centrifugal blower will have been twice heated by reason of its having been first blown forwardly through the heat exchange unit and thereafter drawn backwardly therethrough by the centrifugal blower. Also, under all circumstances, a certain amount of heated air will be blown out and downwardly through the permanently open vents 55.

As an indication of the superior efficiency of our improved heater, it may be noted that the outlet area provided when the lower doors 75, 75 are open is substantially equal to the cross sectional area of the heat exchange element. This is a great improvement over heaters of the type previously known, considering that, in addition, the current of air is given the optimum direction of flow and heat concentration.

Various changes coming within the scope of our invention may suggest themselves to those skilled in the art, and, hence, we do not wish to be restricted to the specific form shown or uses mentioned, except to the extent indicated in the appended claims, which are to be interpreted as broadly as the state of the art will permit.

The word "laterally" is used in the claims to mean a direction away from the axis of the blower or fan.

We claim:

1. A heater of the class described, comprising a heat exchange unit, means for projecting a current of air therethrough, and a casing enclosing said unit, said casing comprising an outwardly curved member substantially closing the front thereof, a portion of said member having vents with means for optionally opening or closing said vents, and means for adjustably opening the remaining portion of the front closure member.

2. A heater of the class described, comprising a heat exchange unit, means for projecting a current of air forwardly therethrough, and a casing enclosing said unit, said casing comprising an outwardly curved front closure element, a portion of said element having vents with means for optionally opening or closing said vents, and

means for partially or wholly opening the remaining portion of said element, said element having a vent adjacent the central portion thereof with means for optionally opening or closing the same, and means for drawing air rearwardly through said central vent and rearwardly through said unit.

3. A heater of the class described, comprising a heat exchange unit, means for projecting a current of air therethrough, and a casing enclosing said unit, said casing comprising an outwardly curved front air discharge closure portion, a segment of which is apertured and provided with means for optionally opening and closing said apertures, and the remaining portion of which closure portion is adjustable and unvented for alternatively closing or opening that portion of the casing front not covered by said apertured segment.

4. A heater of the class described, comprising a heat exchange unit, means for projecting a current of air therethrough, and a casing enclosing said unit, said casing comprising an outwardly curved front portion, said front portion including a member having a spheroidal surface, and adjustable means for providing an opening in said surface, said front portion being rotatable as a whole about an axis parallel to the direction of air flow through said casing and said adjustable means being also operable independently for variably venting said member.

5. A heater of the class described, comprising a heat exchange unit, means for projecting a current of air therethrough, and a casing enclosing said unit and having a circular air discharge opening therein, outwardly curved vented closure means occupying less than 360° of said opening, and adjustable unvented closure means occupying the remainder of said opening for alternatively closing or opening that portion of the casing front not covered by said vented closure means, said adjustable closure means being curved to conform with said first mentioned closure means, whereby it may be rotated into nested relation therewith about the axis of said opening.

6. A heater of the class described, comprising a heat exchange unit, means for projecting a current of air therethrough, and a casing enclosing said unit and having a circular air discharge opening therein, outwardly curved closure means occupying less than 360° of said opening, means for adjustably venting the first mentioned closure means, and adjustable closure means occupying the remainder of said opening, said adjustable closure means being curved to conform with first mentioned closure means whereby it may be rotated into nested relation therewith about the axis of said opening.

7. A heater of the class described, comprising a heat exchange unit, means for projecting a current of air forwardly therethrough, means for inducing a current of air to flow rearwardly therethrough, and a casing enclosing said unit, the front portion of said casing having a central closure element therein, means for adjustably opening the front portion of said casing laterally of said central element, and means for adjustably venting said element, whereby the air drawn rearwardly through said heat exchange unit may be diluted with outside air.

8. A heater of the class described, comprising a heat exchange unit, means for projecting a current of air forwardly therethrough, means for inducing a current of air to flow rearwardly there-

through, and a casing enclosing said unit, the front portion of said casing having an inwardly concave cup shaped element adjacent the central portion thereof, means for optionally and adjustably opening the front portion of said casing laterally of said element, and means for adjustably venting said element, whereby the air drawn rearwardly through said heat exchange unit may be diluted with outside air.

9. A heater of the class described, comprising a heat exchange unit, means for projecting a current of air forwardly therethrough, means for inducing a current of air to flow rearwardly therethrough, and a casing enclosing said unit, said casing having a substantially circular opening in the front portion thereof, means rotatably mounted in said circular opening to form a closure therefor, said closure means having an inwardly concave, cup shaped member adjacent the central portion thereof, means adjustably venting said cup shaped member, and means adjustably venting said front closure laterally of said cup shaped member.

10. A heater of the class described, comprising a heat exchange unit, means for projecting a current of air forwardly therethrough, means for inducing a current of air to flow rearwardly therethrough, and a casing enclosing said unit, said casing having a substantially circular opening in the front portion thereof, means rotatably mounted in said circular opening to form a closure therefor, said closure means having an inwardly concave, cup shaped ventable member adjacent the central portion thereof, said closure member outwardly of said cup shaped member being spheroidal in radial section, and means adjustably venting the latter.

11. A heater of the class described, comprising a heat exchange unit, means for projecting a cur-

rent of air forwardly therethrough, a casing enclosing said unit, the front portion of said casing having a circular air discharge opening therein, a closure element mounted to rotate as a unit in said opening on an axis transverse to the plane of said opening, said closure element including a segmental portion occupying only a part of said opening and having variable venting means associated therewith, and adjustable closure means for the remainder of said opening and adapted to be rotated about the axis of said opening into nested relation with said segmental portion.

12. A heater of the class described, comprising a heat exchange unit, means for projecting a current of air forwardly therethrough, means for inducing a current of air to flow rearwardly therethrough, a casing enclosing said unit, the front portion of said casing having a circular opening therein, a closure element mounted to rotate as a unit in said opening, said closure element including a segmental portion and adjustable closure means occupying the remainder of said opening and adapted to be rotated into nested relation with said segmental portion, and adjustably ventable means obstructing the central portion of said closure element.

13. A heater of the class described, comprising a heat exchange unit, means for projecting a current of air therethrough, and a casing enclosing said unit, said casing having a substantially circular front opening, a substantially spheroidal closure plate covering approximately one-half of said opening, means for adjustably closing the remainder of said opening and rotatable about an axis perpendicular to the face of said opening, and means for adjustably venting said closure plate.

ARNOLD P. HULTGREN.
WALTER G. MITCHELL.
